D. F. DYKE,

SUGAR JAR HOLDER FOR KITCHEN CABINETS,

APPLICATION FILED JULY 27, 1916.

1,202,978.

Patented Oct. 31, 1916.

Inventor:

D. Frank Dyke,

by W. D. Qualls
Attorney.

UNITED STATES PATENT OFFICE.

DARRELL FRANK DYKE, OF CHICAGO, ILLINOIS, ASSIGNOR TO THE SENG COMPANY, OF CHICAGO, ILLINOIS, A CORPORATION OF ILLINOIS.

SUGAR-JAR HOLDER FOR KITCHEN-CABINETS.

1,202,978.

Specification of Letters Patent. Patented Oct. 31, 1916.

Application filed July 27, 1916. Serial No. 111,632.

To all whom it may concern:

Be it known that I, DARRELL FRANK DYKE, a citizen of the United States, and resident of Chicago, in the county of Cook and State 5 of Illinois, have invented a certain new and useful Improvement in Sugar-Jar Holders for Kitchen-Cabinets, of which the following is a specification.

This invention relates to an improved 10 holder intended, primarily, for supporting the sugar-containers or jars in kitchen-cabinets, although, as will hereinafter appear, the device is capable of use for other purposes, and is therefore not to be understood 15 as being limited in its application to that herein shown and described.

The objects of the invention are to produce 20 from sheet-metal and by the art of stamping and bending, a cheap, durable bracket or support, designed to be applied to the partition-board of a kitchen-cabinet, or other wall-like support and adapted to support in a convenient manner and so as to be swung into and out of such cabinet the sugar container or jar usually employed in connection 25 therewith.

Other objects and advantages of the invention will hereinafter appear and the novel features thereof will be particularly 30 pointed out in the claims.

Referring to the drawing: Figure 1 is a side elevation of my device; Fig. 2 is a vertical longitudinal sectional view of the same; Fig. 3 is a front elevation of the same; Fig. 35 4 is a top plan view, the device being shown by dotted lines in a swung out position, and also as applied to a partition or wall-support; and Fig. 5 is a detail in plan of a part of the blank employed showing the same before 40 being bent or folded.

Similar numerals of reference indicate similar parts in all the figures of the drawing.

The device comprises an attaching-plate 45 5, intended to be secured in position to a partition or other wall 10, by means of ordinary screws, and therefore stationary, and a swinging-member 15, pivoted to the attaching-plate in a manner now to be described.

50 The attaching-plate 5, is provided between its ends with punched out screw-receiving holes 6, and beyond the same has its upper and lower ends laterally bent to form parallel ears 7.

The swinging-member 15, the blank from 55 which the same is formed being illustrated in Fig. 5, comprises an upper horizontal branch 16, and an inclined bracing-branch 17. These branches 16 and 17, terminate respectively in ears 18 and 19 which overlap, respectively, 60 the ears 7 of the stationary member and are pivoted thereto by means of rivets 20, whereby the member 15 is capable of freely swinging.

At a point between its ends the blank from 65 which the member 15 is produced, is bent, as at 21, so as to receive and embrace a jar-supporting ring 25. This ring, it will be understood, may be of any shape desired and best adapted to support the container or jar. 70 In the present instance, being intended to receive and support the usual cylindrical sugar-jar employed in connection with kitchen-cabinets, said ring is circular.

At one side of the bend 21, the blank is 75 provided with rectangular extensions 22, and at the opposite side of said bend 21, the blank is provided with triangular extensions 23, there being produced between these two sets of extensions, 22 and 23, intermediate 80 curved recesses 24. When the blank is bent, as at 21, it embraces, at its bent portion, the ring 25. This ring is formed from a suitable length of heavy gage wire and the terminals 26 thereof, extend rearwardly under the upper horizontal portion or branch 16 of the swinging-member. These terminals 26 are clamped in position by means of the extensions 22 of the blank, which, as will be seen, are downwardly and inwardly bent to embrace 90 said terminals. Likewise, also, are the triangular extensions 23 of the blank, bent at an angle to the main portion thereof, so that the edges take under and lend additional support to the ring 25. In this 95 manner it will be seen that the most effective and rigid connection is established between the swinging-member and the supporting-ring.

It will be apparent that by the employment 100 of the described device there is provided an efficient bracket, particularly adapted for the support of a ring for holding the sugar jars usually present in kitchen-cabinets, whereby said jars may be swung 105 into and out of the cabinet for the purpose of storing them or giving access to their contents.

Having described my invention, what I claim is:

1. The hereindescribed bracket, the same comprising a stationary member having an attaching-plate provided with opposite bearings, an angular swinging member having terminals movably pivoted to said bearings, and a jar support located in and embraced by the angle of said swinging member and clamped in position by the metal thereof bent thereabout.
2. The hereindescribed bracket, the same comprising a stationary member having an attaching-plate provided with opposite bearings, an angular swinging member having terminals movably pivoted to said bearings, and a jar support located in and embraced by the angle of said swinging member and at each side of the angle clamped in position by the metal of said member.
3. The hereindescribed bracket, the same comprising a stationary member having an attaching-plate provided with opposite bearings, an angular swinging member having terminals movably pivoted to said bearings, and a jar support located in and embraced by the angle of said swinging member and having its terminals extending rear-

wardly under the horizontal portion of and embraced by the metal of said swinging member.

4. The hereindescribed bracket, the same comprising a stationary member formed with an attaching-plate having upper and lower laterally bent ends forming ears, an angular swinging member terminating in ears pivoted to the ears of the attaching-plate and between the same at one side of its bend having lateral extensions and at the opposite side triangular extensions, a jar supporting ring mounted in and embraced by the angle of the swinging member and having its terminals extending rearwardly under the horizontal portion of the swinging member and embraced by the lateral extensions thereof and at the opposite side of the angle of the swinging member being supported by the bent triangular extensions thereof.

In testimony whereof I have signed my name to this specification in the presence of two subscribing witnesses.

DARRELL FRANK DYKE.

In the presence of—
FRANK J. SENG,
F. H. ELWERT.
